UNITED STATES PATENT OFFICE.

CHARLES L. GOODRUM, OF BROOKLYN, NEW YORK, ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

1,238,130.

Specification of Letters Patent. Patented Aug. 28, 1917.

Application filed October 2, 1916. Serial No. 123,411.

To all whom it may concern:

Be it known that I, CHARLES L. GOODRUM, a citizen of the United States, residing at Brooklyn, in the county of Kings and State 5 of New York, have invented certain new and useful Improvements in Machine-Switching Telephone-Exchange Systems, of which the following is a full, clear, concise, and exact description.

10 This invention relates to private branch exchange telephone systems employing machine switching. Its object is to provide a system of this character wherein the subscribers may interconnect themselves automatically, and wherein certain subscribers can cause the connector to pick out a trunk leading to the main office, from whence the connection may be extended, whereas other subscribers are automatically debarred from 20 using such trunks.

In accordance with this invention the terminals of the restricted lines have impressed upon them current differing in character from that impressed upon those of the non-restricted lines, and a relay is associated with the calling line terminal and operated or not, according to the character of current impressed upon such terminal. This relay, in operating, prepares a circuit which is 30 closed when the automatic switch is set in operative relation to the outgoing trunk group, which circuit includes an electromagnet which operates and renders inoperative the secondary magnet stepping circuit, 35 which is ordinarily automatically closed when the outgoing trunk group is selected.

More specifically, the lines of the restricted subscribers are provided with test terminals which are connected to the opposite 40 pole of the battery from that to which similar test terminals of the lines of the non-restricted subscribers are connected, and a polarized relay is associated with the connector which operates, or not, according to 45 the character of the calling line, and either prepares a circuit which, when the connector is set upon the outgoing trunk group, disables the connector and gives a busy signal back to the calling party, or permits the 50 trunk call to be made, depending upon the character of the calling line.

Referring to the drawing, which is a diagram of a circuit arrangement embodying the invention, the invention will be more

readily understood by describing in detail 55 the operation.

Upon the removal of the receiver at substation A, the line relay LR becomes energized, and in the well-known manner, starts a line finder LF in motion, seeking the calling line. When the finder brushes 1, 2, 3 come to rest upon the calling line multiples 4, 5, 6, the cutoff relay CO is energized to remove the control of the line relay LR from the calling party. Assuming substation A 65 to be a non-restricted line, the polarized relay 7 connected to the finder test brush 3 is not operated. The calling party now actuates the sender S to operate the stepping relay 8 to set the connector C in operative 70 relation to the group containing the calling line. When the relay 8 becomes energized as the finder connects with the calling line, a slow relay 9 is operated by the attraction of the armature of such stepping relay. When, 75 now, the sender S interrupts the line circuit, upon each retraction of the armature of relay 8, an impulse of current is transmitted over the following path to the primary magnet PM of the connector: ground, armature and back contact of relay 8, right armature and front contact of relay 9, conductor 10, connector side-switch arm 11 and its first contact, magnet PM, right armature and back contact of busy relay BR, free pole of 80 battery. Upon the first retraction of the armature of stepping relay 8, a relay 13 is energized, and being slow acting, remains energized while the armature of relay 8 is 85 vibrating. Relay 13, in attracting its right 90 armature, energizes the escapement magnet 45, which is constructed to release the side switch upon its deenergization. When the sender S reaches its normal position and maintains relay 8 energized, the maintained 95 attraction of the armature of relay 8 causes the deenergization of relay 13, which in retracting its armature, deenergizes the escape magnet which releases the side switch into position 2. 100

The calling party now operates the sender S to transmit the units digit of the called number. Upon each retraction of the armature of relay 8, an impulse is sent over arm 41 to the secondary magnet SM, the circuit 105 including the right armature and back contact of relay BR. Magnet SM thus steps the brushes 16, 17, 18 over the selected

group of multiples containing those of the wanted line 19, 20, 21. Upon the first retraction of the armature of relay 8, slow relay 13 again energizes, and in attracting its right armature, energizes the escape magnet. Upon the maintained energization of relay 8, as the sender restores, slow relay 13 becomes deenergized, and in retracting its right armature, deenergizes the escape magnet which releases the side switch into position 3, assuming the line to be idle, which is the case if no ground is present on test multiple 21. As the arm 29 reaches its third contact, ground is applied to the test multiples 21 of the selected line to cause the same to test busy to other connectors and to operate the cutoff relay of such line. In position 3 the escape magnet is again energized over a circuit including arm 22 and the armature and back contact of ringing cutoff relay RCO. The escape magnet, in attracting its outer armature, applies ringing current to the called line over the following circuit: free pole of ringing generator 23, relay RCO, outer armature and front contact of magnet 45, arm 24 and its third contact, brush 17, multiple 20, bell 25, condenser 26, multiple 19, brush 16, arm 27 and its third contact to ground.

30 When the called party removes his receiver, relay RCO attracts its armature, opening the circuit of the escape magnet, which in deenergizing, releases the side switch into position 4, in which position 35 talking current is fed to the called substation B over the following circuit: free pole of battery, left winding of feed coil 28, arm 27 and its fourth contact, brush 16, multiple 19, through the telephonic apparatus at substation B, multiple 20, brush 17, arm 24 and its fourth contact, right winding of feed coil 28 to ground.

Upon the conclusion of the conversation the subscribers replace their receivers. Relay 45 8, in retracting its armature, opens the circuit of relay 9, which, after a slight interval, retracts its armatures, whereupon the following circuit is closed for the release magnet R'M' of the connector, and RM of the 50 finder: armature and back contact of relay 8, inner armature and back contact of relay 9, where the current divides, part passing by way of the outer armature and back contact of relay 9, off-normal contact PON of the 55 finder, to the magnet RM of the finder, the remainder passing by way of conductor 30, off-normal contact P'O'N' to the release magnet R'M' of the connector. Magnet R'M' then locks itself up in a circuit including off-normal contact P'O'N'. When 60 the connector brush shaft reaches its normal position, it opens the off-normal contact P'O'N', thus opening the locking circuit of the magnet R'M', and when the finder brush shaft reaches its normal position, it opens

off-normal contact PON, whereupon the release magnet RM of the finder becomes deenergized.

If the selective line is busy, the multiple 21 is grounded, and when the test brush 18 reaches such multiple and before the escape magnet 45 becomes deenergized, after slow relay 13 opens its circuit, the following circuit is closed for the busy relay BR: ground, multiple 21, brush 18, arm 29 and its second contact, spring 31, controlled by the brush shaft, now closed, to its lower contact, inner armature and front contact of escape magnet 45, inner armature and back contact of slow relay 13, conductor 30, right winding of relay BR, free pole of battery. Relay BR, in attracting its inner armature, locks itself to ground at the armature and front contact of relay 8, and in attracting its outer armature, connects a source of busy tone signaling current 32 to talking conductor 23, and thence to the calling line, to indicate to the calling party that the desired line is busy. When the calling party replaces his receiver, release takes place as hereinbefore described.

Assuming now that the calling party desires a connection with a trunk leading to the main office to which the private branch exchange shown belongs. In that event, the calling party operates his sender to set the connector C in operative relation to the tenth or top group of terminals in the connector. When the connector is so set, contact 34 is closed, and spring 31 is shifted to its upper contact by the connector brush shaft. Now, when the slow relay 13 deenergizes as the sender reaches its normal position, the following circuit is closed to energize relay 35: permanently grounded terminal 36, with which brush 18 engages at the end of the primary movement of the brush shaft when the outgoing trunk group is selected, brush 18, arm 29 and its second contact, spring 31 now closed to its upper contact, relay 35, free pole of battery. Relay 35, in attracting its inner left armature, again energizes slow relay 13 to energize the escape magnet 45, and in attracting its right armature, closes the following self-interrupting circuit for magnet SM: free pole of battery, right armature and back contact of relay BR, magnet SM and its armature and back contact, arm 37 and its second contact, right armature and front contact of relay 35 to ground. The brushes 16, 17, 18 are thus stepped over the trunk group in search of an idle trunk which is indicated by the absence of ground on the test multiple 48 thereof. When the test brush 18 encounters such ungrounded test multiple, relay 35 becomes deenergized, and in retracting its right armature, opens the circuit of magnet SM, thus stopping the brushes upon the seized trunk terminals,

and in retracting its inner left armature, 5 opens the circuit of relay 13, which in de-energizing, opens the circuit of escape magnet 45 which releases the side switch into position 3. In position 3 the escape magnet is again energized over a circuit including arm 22 and the armature and back contact of relay RCO, as described in connection with a call for a party in the private branch 10 exchange, which results in ringing current being applied to the seized trunk to operate a signal at the operator's position to indicate the arrival of a call. The operator responds to such signal by suitable 15 means, and extends the call in the well-known manner.

Assuming now that a restricted subscriber attempts to secure a connection with the central office. The lines of such subscribers 20 are provided with cutoff relays C'O', connected to the opposite pole of battery from that to which the cutoff relays CO of the non-restricted subscribers are connected. The polarized relay 7 is adapted to respond 25 and close contact 43, when the finder brush 3 engages the test multiple 38 of the restricted lines.

When the calling party sets the connector in operative relation to the outgoing trunk 30 group, the contact 34 is closed by the connector brush shaft, and the following circuit is closed for the relay BR: free pole of battery, left winding of relay BR, conductor 39, outer armature and back contact 35 of relay 13, contact 34, to ground at the armature of the polarized relay 7. Relay BR, in attracting its right armature, opens the connection of battery to the secondary stepping magnet SM, thus preventing the 40 trunk hunting operation from taking place, and in attracting its outer left armature, connects a busy tone to the calling line to indicate to the calling party that the connection cannot be had. The relay BR in 45 attracting its inner left armature, locks itself to ground at the armature and front contact of relay 8. When the calling party replaces his receiver, the relay 8, in retracting its armature, opens the circuit of relay 50 9. The retraction of the armatures of relay 9 closes the circuits of release magnets R'M' of the connector and RM of the finder, as hereinbefore described. When the connector brush shaft reaches its normal position and 55 opens contact P'O'N', the magnet R'M' is deenergized. Similarly, when the finder brush shaft reaches its normal position and opens contact PON, the magnet RM is deenergized.

60 What is claimed is:

1. In a telephone exchange system, the combination with telephone lines of different classes, terminals for said lines, means for impressing current of one character on 65 terminals of lines of one class and of an-

other character on those of the other class, a group of trunk lines, an automatic switch wherein said trunk lines terminate, primary and secondary magnets for said switch, a source of current therefor, a relay, means 70 for extending the calling line to said switch and for connecting said relay to the terminal of such line, said relay operating, or not, according to the current impressed on said terminal, means for setting said switch 75 in operative relation to said trunk group, and means thereupon automatically operated if said relay is energized, adapted to open the connection of said source with said secondary magnet. 80

2. In a telephone exchange system, the combination with restricted and non-restricted telephone lines, a source of current, terminals for said lines, the terminals of the restricted lines being connected to the 85 opposite pole of the battery from those of the non-restricted lines, a group of trunk lines, an automatic switch wherein said trunk lines terminate, a polarized relay, means for extending the calling line to said 90 switch and for connecting said relay to the terminal of such line, said relay operating, or not, according to the potential impressed thereon, means for setting said switch in 95 operative relation to said trunk group, and means thereupon automatically operated either to disable said switch or to cause the same to test said group, dependent upon the condition of said polarized relay.

3. In a telephone exchange system, the combination with restricted and non-restricted lines, a source of current, terminals for said lines, the terminals of the restricted lines being connected to the opposite pole of the battery from those of the non-restricted 100 lines, a group of trunk lines, an automatic switch wherein said trunk lines terminate, primary and secondary driving magnets for 105 said switch, a polarized relay, means for extending the calling line to said switch and for connecting said polarized relay to the terminal of such line, said relay operating, or not, according to the potential impressed on said terminal, a sender for operating said primary magnet to set said switch in operative 110 relation to said trunk group, and means thereupon automatically operated either to open the connection of said secondary magnet with said source of current or to cause said magnet to drive the connector over said 115 trunk group, dependent upon the condition of said polarized relay. 120

4. In a telephone exchange system, the combination with restricted and non-restricted subscribers' lines, a source of current, test terminals for said lines, the test 125 terminals of the restricted lines being connected to the opposite pole of the battery from those of the non-restricted lines, a group of trunk lines, a connector wherein said 130

trunks terminate, primary and secondary driving magnets for said connector, a local driving circuit for said secondary magnet to cause said connector to test said trunks, a 5 polarized relay, means for extending the calling line to said connector and for connecting said relay to the calling line test terminal, said relay operating if the line is a restricted line, a relay associated with 10 said connector and adapted to render inoperative the actuating means for said secondary magnet, a circuit for said relay including a contact of said polarized relay and a contact operated by the connector shaft and 15 closed when the connector is set in operative relation to the trunk group.

5. In a telephone exchange system, the combination with restricted and non-restricted subscribers' lines, cutoff relays and 20 test terminals therefor, the test terminals and cutoff relays of the restricted lines being connected to the opposite pole of the battery from the test terminals and cutoff relays of the non-restricted lines, a connector wherein 25 said lines terminate, primary and secondary stepping magnets therefor, a sender adapted to operate said magnets to set said connector on any line, a group of trunks terminating in said connector, a self-interrupting circuit 30 for said secondary magnet adapted to cause said connector to test said group automatically, a polarized relay, means for extending the calling line to said connector and for connecting said relay to the calling line test 35 terminal, said relay operating if the line is a restricted line, a relay associated with said connector and adapted to open said self-interrupting circuit, a circuit for said relay including a contact of said polarized relay 40 and a contact operated by the connector shaft and closed when the connector is set in operative relation to said trunk group.

6. In a telephone exchange system, the combination with subscribers' telephone 45 lines divided into classes, a connector, a driving magnet therefor, a group of trunks terminating therein, a sender associated with the calling line for controlling said magnet to set said connector in operative relation to 50 said trunk group, driving means thereupon automatically operated to cause said con-

nect to test said group, a relay adapted to render said driving means inoperative, means associated with the calling line and dependent upon its character for controlling said relay and means controlled by the calling party for thereafter releasing the connector. 55

7. In a telephone exchange system, the combination with telephone lines divided 60 into classes, test terminals therefor, sources of current of different character connected thereto, a connector, a driving magnet therefor, a group of trunks terminating in said connector, a sender associated with the calling line for controlling said magnet to set 65 said connector in operative relation to said trunk group, driving means thereupon automatically operated to cause said connector to test said group, a relay adapted to render 70 said driving means inoperative, and means for operating said relay, or not, dependent upon the character of the current impressed upon the test terminal of the calling line.

8. In a telephone exchange system, the 75 combination with restricted and non-restricted subscribers' lines, test terminals therefor, means for impressing current of different character upon said test terminals, a connector, a group of trunks terminating therein, primary and secondary stepping magnets for said connector, a sender adapted to operate said magnets to set said connector on any line, a self-interrupting circuit for 80 said secondary magnet, a discriminating relay (7), means for extending the calling line to said connector and for connecting said relay to the calling line test terminal, said relay operating if the line is a restricted one, a relay (35) associated with said connector 85 for closing said self-interrupting circuit, said relay operating when the trunk group is selected and being maintained energized as long as busy trunks are encountered, and a relay (BR) operated when the trunk group 90 is selected by a restricted line and disabling said self-interrupting circuit. 95

In witness whereof, I hereunto subscribe my name this 29th day of September, A. D. 1916.

CHARLES L. GOODRUM.
